UNITED STATES PATENT OFFICE.

ISAAC STROUSE, OF NEW HAVEN, CONNECTICUT.

DESIGN FOR A CORSET.

SPECIFICATION forming part of Design No. 12,687, dated January 10, 1882.

Application filed December 15, 1881. Term of patent 7 years.

To all whom it may concern:

Be it known that I, ISAAC STROUSE, of New Haven, in the county of New Haven and State of Connecticut, have invented a new Design for Corsets; and I do hereby declare the following, when taken in connection with the accompanying drawing and the letters of reference marked thereon, to be a full, clear, and exact description of the same, and which said drawing constitutes part of this specification, and represents a side view, showing the hip-section complete.

This invention relates to a design for the ornamentation of that part of a corset commonly called the "hip-section"—that is to say, the part of the corset between the front and back, and which extends from under the arm down over the hip; and the design consists in the representation of cords or ribs in series, as shown in the accompanying illustration and hereinafter described.

Transversely across the section, at the center, is the representation of a series of ribs, *a*, and

between that series and the upper end is a second transverse series of ribs, *b*, and between the center series and the lower edge is a transverse series, *c*, leaving a space, *d*, at the top and *e* at the bottom, and also a space, *f*, between the series *a* and *b* and a space, *g*, between the series *a* and *c*. These respective spaces are filled by the representation of vertical ribs, as shown in the accompanying illustration.

I claim—

The design for the hip-section of a corset, consisting of the representation of transverse series of ribs *a b c*, leaving spaces *d* at the top and *e* at the bottom, and *f* and *g* between the series, the said spaces filled by the representation of the vertical ribs, as shown in the accompanying illustration.

ISAAC STROUSE.
